UNITED STATES PATENT OFFICE.

GEORGE W. MILLS, JR., OF CINCINNATI, OHIO, ASSIGNOR TO THE PHILIP CAREY MANUFACTURING COMPANY, A CORPORATION OF OHIO.

SHINGLE.

Application filed September 26, 1921. Serial No. 503,431.

My invention is for an improvement in shingles and is more especially an improvement in shingles of the flat type such as prepared shingles, asbestos slate shingles and other flat shingles. My invention could in some of its features be used upon curved roofing tile or on wood shingles if desired. In the proper laying of shingles, especially of the flat type, it is advisable that a given portion only be exposed to the weather and it is essential that the shingles be spaced some distance apart in order that the proper decorative effect be given to the roof when finished and to allow for expansion and contraction due to temperature changes. To secure this proper positioning of the shingle and to facilitate the laying of it I have provided the shingle with suitable marking, which may be of any suitable form such as dots, dashes or lines, but I prefer to use lines of a different color or shade from the surface of the shingle and more especially I prefer the use of black lines so arranged that the lines will be visible to the person who is laying the shingles and in the finished roof will be visibly located so as to simulate shadow effects and thereby enhance the appearance of the finished roof.

In one form of my invention I have found that I can utilize the portion of the shingle exposed to the weather in conjunction with my marking to carry a part of a complete design so arranged that when the shingle is in place, breaking joints with the two shingles underlying it, the design will be brought into register with a portion of the design on each of the two underlying shingles, while the marking line, to represent the distance apart of the shingles; and the portion of the design of the shingle on the second row beneath would serve to complete the figure of the design and thereby provide a roofing which had a design on it simulating curved tile or the shape or form of other roof tiles depending on the design used. To do this I provide the exposed end of the shingle with the design preferably in duplicate so that each shingle represents in part a portion of two figures of the design while the underlying shingle and the shingle above would complete the design figure. Of course a shingle could have on it a portion of, or the whole of, a single figure or design if desired but I prefer to

make mine as shown in Fig. 2 with a portion of two figures on the exposed end.

I have also found that by arranging the marking lines, for the proper spacing and laying of shingles, to simulate shadow effects that a shingle, even though comparatively thin, may be given the appearance on the roof of substantial thickness. This appearance is one of the results desired by architects and others in building of finer residences. The use of prepared shingles and other thin flat shingles for such structures, notwithstanding their fire protection and weather-proof qualities have been objected to because they gave to the roof a flat effect. This is overcome by my invention.

In the drawings I have shown two forms of my invention; Fig. 1 being the ordinary prepared slate surfaced shingle which is formed of a felt base saturated with a bituminous material, coated with a similar bituminous material and then surfaced with a mineral surface such as slate granules. In Fig. 2, I have shown a similar form of prepared slate surfaced shingle. In Fig. 1, I have divided the shingle into three portions A, B, and C. The portion A being the portion which in the finished roof will be visible and will show an area of mineral, preferably slate, surfacing or other suitable surfacing. The portions B and C may be of the same finish as the area A or the mineral surfacing may be omitted entirely from these portions or covered by any suitable material such as a bituminous paint. The lines or markings D, F and H in the preferred form of my invention will be black and preferably of a bituminous material or they may be made with mineral particles of a different color or shade. They may be made by painting, by surface embossing or in any suitable manner. Of course the markings and the design must be of a character that will resist the effect of exposure to weather conditions. Such materials are well known to those skilled in the art. In the preferred form of my invention I also prefer to arrange the marking, to represent the distance apart of shingles in the same row, of such width as to show a black space only between the two shingles overlapping the shingle so that the black line will be visible the full width of the space between adjacent shingles except where that

space is visible above $\frac{1}{2}$ or $\frac{3}{4}$ inches from the extreme lower end of the space as shown in Figure 1 where I have left the area of surfacing A exposed for the purpose of accentuating the shadow like effect between shingles and giving the optical illusion of depth or thickness of shingle. To further increase the optical illusion of thickness of shingle and give the effect in a finished roof of shingles having a thick lower or butt end I have arranged the marking lines D and H which separate respectively the area A and B, and A and C of substantial width having them at their adjacent ends provided with oblique angles E and I which likewise assist the illusion of thickness. Of course where a shingle is thick as in some asbestos slate shingles or tile shingles the marking lines D, F and H would not have to be solid and of substantial width but could merely be a comparatively fine line or dots or other suitable markings. In such a shingle if desired the edges of the shingles could be darkened or provided with a contrasting color or shade, to the surface of the shingle, to give shadow like effects. My invention could also be carried out by having the shadow mark and spacing mark arranged partly on each of two adjacent shingles or the surface of the shingle at the edge could be provided with contrasting color or shade for the purpose of giving the shadow effect. In making prepared slate surfaced shingles I found that the edge of the shingles, due to the color of the slate, had a visible line of color contrasting with the black of the saturated felt base and coating into which the slate was embedded, this I also prefer to overcome and do so by covering the slate at the edge with the same or similar material to that used in making the other markings. The shadow line F could extend all the way to the top of the shingle as shown or could be discontinued at any point below the top such for instance as shown in Figure 2, as it need only be of length to give the desired effect between the next two above shingles and to show the proper spacing of same. In Figure 2, I have shown a prepared mineral surfaced shingle provided with markings for laying the shingle and with the portion of the shingle which is to be exposed to the weather having a portion of two figures of a design on it. This design is formed preferably by covering portions of the mineral surfacing with a bituminous material arranged so as to create the optical illusion of shadow lines whereby the effect is given of a curved surface and not a flat one. In order to lay shingles so that each row broke joints with the next adjacent row, to make a roof waterproof to properly space the shingles apart to allow for expansion and contraction and to obliterate the joint or

space between shingles while giving the effect of individual members forming an entire roof, I have so arranged the design that the complete effect is given by utilizing two or more shingles, a portion of the design being on each of the shingles and I have so arranged the design that it is the marking to facilitate the laying of the shingles. 70

In Figure 2 as in Figure 1 the shingle is divided into three areas A, B and C. 75 The area A being provided as shown in the drawing with a design which when laid in place with the next adjacent shingles above and below, gives the effect of a curved tile; the areas B and C being the areas which are 80 covered by the next two above adjacent shingles which have the same design on them as shown in Figure 2. When in place on the roof the design on the left side of area A will register with the design on the right 85 area of the next below shingle and the marking line F and portion of the design on the second below shingle will complete one figure of the design which as shown is a tile design. The upper portion of the design in 90 the area A of Fig. 2 represents the marking lines D and H of Figure 1 so arranged that in conjunction with line F, which acts likewise in the dual capacity of a marking line and a portion of the design, form 95 the marking showing the position of the next above shingles. The right angle of the lower left hand of area A Figure 2 is brought into register with a similar right angle on another shingle formed by the 100 marking F and the edge H of the design and likewise the angle on the lower right, area A, of Figure 2 is brought into register with a similar right angle formed by the 105 edge D of the design and the marking line F, thereby properly spacing the shingles as to the distance apart and likewise properly spacing them as to the amount to be exposed to the weather.

My invention could also be applied to 110 what are known as strip shingles, that is strips forming a plurality of shingles such as the ordinary strip shingle which is on the market having four shingle tabs or ends. 115

Claims:

1. A shingle having surface markings, in contrast to the surface of the shingle, arranged laterally and longitudinally of the shingle, said laterally-arranged marking adapted to position the amount of overlap of the next above shingles and said longitudinally-arranged marking adapted to position the distance apart of the next above shingles, said markings being exposed, when said shingle is laid with others, to create shadow effects below the edges of, and along the space between, the next above shingles. 120

2. A shingle having a surface marking in contrast to the exposed surface of said shingle extending through a portion of the 125

longitudinal center thereof adapted to position the space apart of the next two above shingles and to create a shadow effect therefor.

5 3. A shingle provided with an area on the part adapted to be exposed having thereon a design, said design having portions each bearing a predetermined relation to the marginal edges of said shingle whereby when a 10 portion of the design on said shingle is brought into register with a portion of the design on a similar shingle the amount of the shingle to be exposed and the distance apart of overlapping shingles will be fixed, 15 said design remaining entirely exposed.

4. A roofing formed of a plurality of shingles each provided with surface markings arranged laterally and longitudinally thereof, in contrast to the surface exposed 20 to view and creating shadow effects, said markings determining the amount of overlap, and the distance apart of the next above shingles.

5. A shingle provided with an area adapted to be exposed having thereon a design adapted to give an ornamental effect to a roof, said design having portions each bearing a predetermined relation to the marginal edges of said shingle whereby 25 when the design on said shingle is brought into register with portions of similar designs on overlapping shingles said over-

lapping shingles are spaced apart the desired distance and the amount of the exposed portion of said shingle is fixed, said 35 design remaining entirely exposed.

6. A shingle having an area adapted to be exposed having thereon a design having duplicate portions on opposite sides of the longitudinal medial line of said shingle each 40 bearing a predetermined relation to the marginal edges of said shingle whereby when said portions are each brought into register with opposite portions of the designs on similar overlapping shingles the amount of 45 overlap and the distance apart of the overlapping shingles will be fixed, said design remaining entirely exposed.

7. A shingle having an end area adapted to be exposed, duplicate designs arranged on 50 said area, a longitudinal marking extending upward from the said designs all so arranged that in laying said shingles the design on one side of a shingle will register with the design on the opposite side of the 55 overlapping shingle, whereby the overlapping shingles will be spaced as to the distance apart and the amount of overlap, and the said longitudinal marking will complete 60 the design between adjacent shingles.

In testimony whereof, I have signed my name to this specification.

GEO. W. MILLS, JR.
